UNITED STATES PATENT OFFICE.

JOSEPH HEELEY, OF WIGAN, ENGLAND.

SLICER.

992,559.

Specification of Letters Patent.

Patented May 16, 1911.

Application filed February 26, 1910. Serial No. 546,160.

To all whom it may concern:

Be it known that I, JOSEPH HEELEY, a subject of the King of Great Britain, residing in Wigan, in the county of Lancaster, in the 5 Kingdom of England, have invented a certain new and useful Slicer, of which the following is a specification.

This invention has for its object a knife or cutting device to cut loaves, bacon, 10 vegetables and other substances into slices.

The invention will be understood from the following description, reference being had to the accompanying drawings, in which;

15 Figure 1 is a perspective view of a slicer illustrating my invention; and Fig. 2 is a similar view indicating some changes in detail.

In carrying the invention into effect, I 20 provide a knife A pivoted at one end to a link B, and at the other end provided with a handle C. The link at its upper end is hung from a frame D, the base of which is secured to a plate E in any suitable manner, 25 as by soldering or by clamps, as shown in Fig. 2, and this plate E it of course will be understood, is secured to or rests upon a table or board. This frame or guide D is bent upward at each end of this plate E 30 to the required height. The frame is slotted, or made with a pair of members side by side so as to leave a slot F between, in which the knife A can play up and down and act as a guide. On the base plate E is mounted 35 a fence G, and secured to the plate is a lug H in which is screwed a threaded pin I coupled at the end to the fence G, so that by turning the pin I the fence G is moved nearer to or farther away from, the blade 40 A, to determine the thickness of the slices to be cut, and the fence is slotted at J so as to clear the lug H. The fence G can be flanged so as to lie as close as desired to the knife A. The base plate is slotted at K 45 opposite the slot F in the frame D, so as to let the knife cut through the loaf or other article, and prevent its cutting edge coming into contact with the metal plate E, which might blunt it, also a small finger can be

provided at the handle end of the knife, 50 which will form a stop against the table. The coupling of the knife end to the link, is preferably effected by a screw L which can be removed when it is required to uncouple the knife A for sharpening, and in 55 order to enable the head of this screw to pass through the slot in the frame, the slot is enlarged at one place so as to enable it to pass through.

The mode of action is as follows:—The 60 fence G having been set so as to cut a slice of the required thickness, a loaf M is placed against the fence, and the knife by a downward movement of the handle C, cuts it into slices. The link B by which the knife is 65 hung at one end, enables the knife A to be held horizontal while cutting, or at various angles of inclination, or it enables the knife to have a reciprocating movement imparted to it. The full lines show the blade A in a 70 raised position, the dotted lines show it at the bottom of its downward stroke. If desired, two or more knives can be provided in one handle set parallel to each other, in which case the machine will cut more than 75 one slice at a time. When cutting substances other than loaves, the action is similar.

I declare that what I claim is:—

1. In a slicer, the combination with a 80 suitable base, of a guiding frame secured thereto and having upwardly extending ends slotted to form guides for the reciprocating knife, a cutting blade having a pivoted link connecting one end thereof with the upper 85 end of one of said frame ends, whereby a reciprocating as well as a vertical, movement may be imparted to said knife, the link as well as the knife being guided in the slot of said end member of the frame. 90

2. In a slicer, the combination with a suitable base, of a guiding frame secured thereto, and having upwardly extending ends slotted to form guides for the reciprocating knife, a cutting blade having a pivoted link 95 connecting one end thereof with the upper end of one of said frame ends, whereby a reciprocating as well as a vertical move-

ment, may be imparted to said knife, the link as well as the knife being guided in the slot of said end member of the frame, said base member of the guide and the supporting plate being also slotted to allow the knife to pass therethrough.

In witness whereof, I have hereunto

signed my name this 9th day of February, 1910, in the presence of two subscribing witnesses.

JOSEPH HEELEY.
